Claims priority, application Great Britain Aug. 25, 1959
5 Claims. (Cl. 162—103)

This invention relates to the manufacture of articles from fibrous material and is more particularly, but not exclusively, concerned with the production of a fibrous preform. It is well known to manufacture articles from fibrous material by producing a deposit of the fibrous material onto a suitably shaped mould immersed in a bath of aqueous slurry of the fibrous material. Briefly speaking, the method involves strongly agitating a bath of the slurry so that the fibrous material is well distributed throughout the bath and so that the material is prevented from settling out of the water in the bath, and sucking the slurry towards the mould thereby to form a layer of fibrous material on the mould. After the desired thickness of the layer has been achieved, the mould, plus the layer is raised above the surface of the bath, and the layer is removed from the mould for further treatment. When it is desired to secure attachments to the body thus moulded it has been the usual practice to secure these attachments by the use of adhesives or by mechanical devices such as rivets, staples, clips or the like which devices penetrate the moulded article. It will be appreciated that when an element is secured by means of an adhesive, the connection is essentially a surface fastening as it is only at the regions of contact between the adhesive and the moulded body and the adhesive and the attachment that adhesion can be produced.

In the drawings:

FIG. 1 is a transverse sectional view of a molded body made in accordance with the principles of the present invention;

FIG. 2 is a view similar to FIG. 1 but showing a modified form of the body shown in FIG. 1; and

FIG. 3 is a view similar to FIG. 1, but showing a modified form of the body shown in FIG. 1.

According to a first aspect of the present invention there is provided a method of connecting to a moulded body an anchorage for mechanical securing means, comprising incorporating an insert in the fibrous body whilst the latter is being moulded, which insert acts as the anchorage. For a better understanding of the invention one constructional form thereof will now be described in greater detail in relation to the accompanying drawing.

In this constructional form the article 1 to be moulded is produced in the conventional manner upon a mould 2 which has the desired shape. At those locations where it is desired to provide a fixing attachment 3, the mould wall is apertured as at 4 to receive a hollow upstanding tube 5. The tube 5 has an outwardly directed peripheral collar 6 located intermediate of the end thereof. When the tube engages the mould the collar bears against the outer surface of the wire screen 7, which is conventionally provided on the outer surface of the mould so that one portion of the tube enters the mould wall, whilst the remainder of the tube, projects from the mould. A hollow cylindrical plug, or insert 8, which is a close sliding fit on the tube is mounted on the remainder of the tube 5. The external diameter of the collar on the

tube is less than the external diameter of the plug. The insert or plug is covered by very open mesh metal wire gauze screen 9 the latter being in effect a cylindrical member closed at its uppermost end and open at its lowermost end. The lowermost end of the wire screen is opened out to provide an outwardly directed peripheral flange 10. When the mould and the mesh covered plug 8 are immersed in the aqueous solution of the fibrous material and suction is applied to the interior of the mould the fibres are sucked towards the mould thereby to deposit themselves on the outer surface of the mould, and on the wire screen surrounding the plug. The fibrous material deposits itself around the walls of the upstanding plug and on the upper end thereof. In addition it has been found that there is a general thickening of the thickness of the material deposited on the plug in the region where the tube engages the mould. This thickening extends over an annular area in the vicinity of the plug or insert thereby providing a stronger anchorage for the insert. After the desired amount of material has been deposited upon the mould the mould is removed from the fibrous bath before subsequent treatment such as drying etc. The wire screen surrounding the insert provides a reinforcement for the plug. The completed fixing attachment 3 includes the fiber-covered plug 8 and screen 9.

If desired, as shown in FIG. 2, the plug may be a solid cylinder, and alternatively the plug could have a shaped exterior surface and can be made of any material suitable for mechanical attachment. The plug itself can also contain an additional insert to assist in the mounting of the attachments, such as for example a threaded tube 11, as shown in FIG. 3.

What I claim is:

- 35 1. A method of connecting to a moulded body an anchorage for a mechanical securing means, comprising the steps of introducing a tube member into a suction mould, so that a part of the tube member projects from the mould surface, placing an insert on the tube member, placing a tubular screen member over the insert so that the inner end of the screen member is adjacent to a wire mesh screen previously positioned on the mould, and causing moulding material to deposit on the mould and on the tubular screen member to form the moulded body.
- 45 2. A method as claimed in claim 1, wherein the insert is in the form of a hollow tube.
3. A method as claimed in claim 2, wherein an additional insert is introduced into the hollow tube.
- 50 4. A method as claimed in claim 2, wherein an additional insert is introduced into the hollow tube, the additional insert having a threaded portion.
5. A method as claimed in claim 1, wherein the insert is solid.
